UNITED STATES PATENT OFFICE.

ANDREAS J. PALMBERG, OF BOSTON, MASSACHUSETTS.

IMPROVEMENT IN IRONING-TABLES.

Specification forming part of Letters Patent No. 142,645, dated September 9, 1873; application filed June 4, 1873.

To all whom it may concern:

Be it known that I, ANDREAS JOHANSSON PALMBERG, of Boston, in the county of Suffolk and State of Massachusetts, have invented certain new and useful Improvements in Ironing-Boards; and I do hereby declare the following to be a full, clear, and exact description of the invention, such as will enable others skilled in the art to which it pertains to make and use it, reference being had to the accompanying drawings, which form part of this specification.

My invention relates to improvements in ironing-tables, constructed in such a manner as to be taken apart for transportation, or otherwise, so as to be packed in as small compass as possible. Two portable arms can be attached to a pair of beams running under the board and metallic supports, for the purpose of ironing sleeves and smaller articles. The said arms project above the ordinary ironing-board, and, therefore, when they are used, the operator would have to raise his arm and iron inconvenient for comfort, for which reason I lower the feet of the board by using movable feet resting on casters, that may be swung around hinges, whereby the board is lowered about the same distance as the sleeve-boards project above the ordinary board. The cross-bar between the supporting-legs for the board is attached to the said supports by means of slotted plates fitted over projecting lugs on the ends of the cross-bar, by which arrangement the cross-bar can be easily removed from the supports during transportation.

On the drawings, Figure 1 represents a ground plan. Fig. 2 represents a side elevation. Fig. 3 represents an end view seen from A on Fig. 1. Fig. 4 represents a longitudinal section on line A B, shown on Fig. 1. Figs. 5 and 6 represent details of the feet with their movable casters; and Fig. 7 represents an enlarged end view of the slotted plate, by which the cross-bar is attached to the supports for the board.

Similar letters refer to similar parts whenever they occur on the different parts of the drawings.

a represents the board, with its hinged extensions *b b*, as usual. To the under side of

the board *a* are attached the metallic supports *c c*, as shown. Between the supports *c c* is attached the cross-bar *d* by means of the projecting lugs *e e e e* projecting through holes made for that purpose in the supports *c c*, and the slotted plates *f f* having slot-holes *g g*, made in such a manner as to allow the T-headed lugs *e e* to be inserted therein and locked together to the supports *c c* simply by sliding down the plates *f f* over the T-headed lugs *e e* in a position as fully shown in Fig. 7. The object of this arrangement is to provide an easy mode of detaching the supports from the cross-bar during transportation or otherwise. Two rods, *h h*, are inserted through suitable perforations made in the upper part of the supports *c c*, as shown in Figs. 2 and 3, and are held, furthermore, in position by being inserted through suitable guide-pieces *i i* attached under the board *a*. Over the rods *h h* is first slipped a metallic rest, *k*; afterward the piece *l*, tapped for the reception of the screw *m*, that is provided with the hand-wheel *n*, that serves also as a rest for the heated flat-iron during the operation. A rest, *o*, very similar to the one *k*, heretofore described, is at last slipped over the ends of the bars *h h*. The upper ends of the rests *k* and *o* are perforated with suitable holes, through which the end of the sleeve-board *p* is inserted. The end of the sleeve-board *p* has a slot, *q*, Fig. 1, for the purpose of allowing the end of the board *p* to be put in its proper place without interfering with the set-screw *m*. On the top of the end of the sleeve-board *p* rests another smaller sleeve-board, *r*, placed at right angles to the larger board *p*. The smaller sleeve-board *r* is also provided with a slotted opening, *s*, so as to allow of the board *r* being put in its proper place without interfering with the screw *m*. A small clamp, *t*, resting in the upper parts of the rests *k o*, bridges over the rear end of the sleeve-board *r*, by which and the screw *m* it is held firmly in place.

As will be seen from the above, the different parts of the ironing-board can easily be detached from each other, and the whole enclosed in a very small case for transportation.

The ironing-table *a* is made of a proper and

convenient height from the floor, so as to be comfortable to work upon; but when the sleeve-boards *p* and *r* are used, it will be seen that they would be too high from the floor to be comfortable to work upon. To avoid this difficulty I have the casters *u u u u* mounted upon hinged supports *v v v v*, hinged to the lower ends of the legs *c c* in a manner as shown in Figs. 3, 5, and 6. Fig. 5 represents the caster in the position when the board *a* is used, and Fig. 6 represents the caster as swung back around its hinge-pin to a position as used when the operator works on the sleeve-boards *p* and *r*. Thus it will be seen that, by folding up the casters, as shown in Fig. 6, the height of the board is lowered a distance about equal to the space between the sleeve-board *p* and ironing-board *a*.

When the casters are in the position as shown in Fig. 5 they may be held in place by means of a small pin, *w*, or its equivalent.

What I wish to secure by Letters Patent, and claim, is—

1. The combination, with an ironing-table, *a*

c c, of the sleeve-boards *p r*, rests *o k*, and the bars *h h*, with the clamp *l* and its screw *m n*, for the purpose of being easily detached from the ordinary ironing-table, as herein shown and described.

2. The combination, with the sleeve-boards *p r* and their connecting parts, the table *a*, and standards *c c*, of the hinged casters *u v u v*, for the purpose of lowering the board when the said sleeve-boards are used, as herein shown.

3. In an ironing-table, the combination, with the supports *c c*, of the cross-bar *d*, provided with **T**-headed lugs *e e* and the slotted fastening-plates *f f*, as and for the purpose set forth.

In testimony that I claim the foregoing I have hereunto set my hand this 27th day of May, 1873.

ANDREAS JOHANSSON PALMBERG.
